UNITED STATES PATENT OFFICE

JOHN FRODSHAM, OF BERKELEY, CALIFORNIA.

ROTARY PUMP.

1,329,895.

Specification of Letters Patent.

Patented Feb. 3, 1920.

Application filed April 22, 1919. Serial No. 291,845.

To all whom it may concern:

Be it known that I, JOHN FRODSHAM, a citizen of the United States, residing at Berkeley, in the county of Alameda and State of California, have invented new and useful Improvements in Rotary Pumps, of which the following is a specification.

This invention relates to a rotary pump and particularly pertains to that class of pump disclosed in my patent entitled "rotary pump," dated March 4, 1919, and bearing the number 1,296,500.

It has been found in the operation of rotary pumps that there is considerable end thrust upon the vanes and the rotor of the pump and that there also is difficulty in operation, due to the fact that obstructing material passes through the inflow pipe and prevents the rotation of the rotor, often breaking the vanes or bending the rotor shaft. It is the principal object of the present invention to provide a pump of the character described, which is so constructed as to eliminate undesirable end thrust in the rotor and the vanes and at the same time to provide a pump structure which will prevent incoming material from obstructing the movement of the pump, thus preventing damage thereto.

The present invention contemplates the use of a pump having a casing, the interior of which forms a cylindrical shaped chamber. Mounted within this chamber is a rotor carrying a plurality of vanes extending radially within slots formed upon the opposite side of the rotor. In the present instance, the rotor is formed with a plurality of angular flanges which pass into circular grooves in the interior of the casing. These flanges are formed through an eccentric portion of the casing wall which causes the vanes to move inwardly during the operation of the pump, an eccentric cam being provided to automatically force the vanes outwardly as the pump continues to operate.

The invention is illustrated by way of example in the accompanying drawings, in which—

Figure 1 is a view through the pump in central vertical section, disclosing the intake and outlet ports, the rotor therein and the cylinder circumscribed by said rotor.

Fig. 2 is a view in vertical section as taken on the line 2—2 of Fig. 1 and more clearly shows the formation of the rotor, the manner in which the vanes are operated,

and the slots in the eccentric portion of the casing.

Referring more particularly to the drawings, 10 indicates a pump casing here shown as having a lower half 11 and an upper half 12. These casing halves are intended to be bolted together by cap screws 13 which extend through flanges formed upon the opposite side of the halves. The parting line of the casing is along a horizontal plane coinciding with the point of radius of the lower wall of the casing, this wall being entirely concentric and also concentric with the grooves which are formed in the upper casing half.

The upper casing half is formed with an inlet passageway 14 and an outlet passageway 15. The inlet passageway extends horizontally and tangentially to the chamber within the casing while the outlet passageway is shown as extending at an angle to the vertical and tangentially to the wall. The outer wall of the passage 15 is tangent to the inner wall of the casing while its opposite wall is shown to emanate from the point of intersection of the transverse center of the pump with the inner wall thereof. This arrangement will insure that large solid pieces flowing into the pump will be obstructed as the incoming liquid strikes a vertical deflecting wall. The arrangement also eliminates the possibility of binding the rotor by material as it passes out through pipe 17. The open ends of the passageways are internally threaded to receive an intake pipe 16 and an outlet pipe 17.

In order that the passageways may be satisfactorily cleaned when desired, removable plugs 18 are secured into the side walls of the casing and allow admittance to the interior of the casing and passageway. The upper casing half is formed with an eccentric wall portion providing a plurality of cam members 19, 20, 21 and 22.

The eccentric walls of these members extend from the dividing line of the casing halves and represent the reciprocal movement of the vanes of a rotor, afterward, to be referred to. The cam portions 19 to 22 inclusive are spaced apart as shown in Fig. 2, to form a plurality of end thrust grooves 23, 24 and 25. These grooves are rectangular in section and only extend the length of the cams themselves as the lower half of the casing is perfectly smooth and presents a full length bearing surface for the vanes.

of the rotor. The opposite ends of the casing halves are closed by means of heads 26 and 27. These heads are circular and are bolted into position by cap screws 28 and 5 each of the heads is formed with a bearing 29 carrying a stuff box 30. The stuff box is provided to receive a rotor shaft 31, which extends completely through the cylinder and provides a mounting for a circular 10 rotor 32.

The rotor 32 is mounted concentrically with the lower interior wall of the casing half 11 and the wall of the grooves 23 to 25 inclusive, it being noted that in Fig. 1 these 15 grooves and the lower wall portion are considered to be continuously circular and concentric with the rotor shaft 31. The cylindrical rotor is formed with a plurality of flanges 33 which agree in their spaced relation to each other to the grooves 23 to 25 formed in the upper casing half 12. These 20 flanges coöperate with the grooves to prevent end thrust on the rotor when it is in operation and thus hold it in a practically 25 fixed path of travel preventing all binding against the opposite casing heads 26 and 27. The rotor is formed with a plurality of radial slots 34. These slots are here shown as being at right angles to each other. Each 30 slot is fitted with a blade or vane 35 which may reciprocate along its slot and is designed to extend outwardly therefrom and to bear against the wall of the lower casing half and the eccentric face of the cam portions 35 19 to 22 inclusive. Inward reciprocal movement of each blade is, of course, produced by this eccentric face of the cam portions mentioned. The outward movement of the blade is positively produced by 40 a pair of eccentric cams 36, one of which is secured at each end of the cylinder and mounted upon the cylinder heads 26 and 27. By the provision of these cams, as particularly shown in Fig. 1, the space between 45 the eccentric wall of cam portions 19—22 and the cams 36 or the circular wall of the lower casing half and the cams will always be the same, this space being the width of the blade 35, thus holding the blade against any vibration 50 endwise while at the same time end thrust of the blade will be prevented by their bearing action upon the casing heads 26 and 27.

In operation of the present invention a 55 fluid under compression may be delivered to the pipe 16 when the device is to be used as a motor or may be allowed to flow through this pipe when the device is used as a pump. When a pump action is provided, the fluid 60 will pass into the pipe 16 and will be deflected downwardly by striking the curved wall 37 of the passageway 14. This downward deflection will act to throw the fluid against the exposed blade 35 of the rotor 65 and will cause the rotor to operate in the

direction of the arrow *a*, as indicated in Fig. 1. As the rotor is forced around on its cycle of travel, the fluid which has initially entered through the pipe 16 will finally reach the outlet passageway 15 and be 70 forced upwardly through the pipe 17. The forcing action of the vanes 34 will be gradually diminished upon their upward movement, due to the fact that they will be retracted as they engage the eccentric face of 75 the cams 19 to 22 inclusive and when the blade has reached the upper edge 38 of the passageway 15 it will be in an entirely re-ceded position, as shown in Fig. 1. These blades will be projected into the chamber 80 of the pump casing by the action of cam 36.

In considering the action of the pump, attention is particularly directed to the peculiar action of the curved inlet wall 37 and the vertical wall 38. The inlet wall will act 85 to deflect any large pieces of solid material down into the large open portion of the casing, as it is formed between the casing wall and the outer circumference of the rotor. When this material is delivered to the exhaust passageway 15, it will not be liable to bind against the cam faces of the eccentric members 19 to 22 inclusive, but will be thrown upwardly into the passageway 15. Due to the fact that the wall 38 extends 95 vertically, there will be small chance of obstruction at this point, and the material will pass out through the pipe 17.

It will be noted that the fluid will pass into the cylinder at a uniform rate of 100 flow and will be equally distributed over the surface of the rotor and between the flanges thereof. This will act to hold the rotor in balance while the fluid is being carried around the casing and delivered to the outlet pipe 17. It will further be noted that the pump here shown is decidedly cheap to manufacture and as it is formed of parts simple in their construction and readily assembled, will produce an article quite desirable for the trade, at the same time possessing the advantages of not being liable to become broken or rendered inoperative, due to obstruction in the pipe or to objectionable wear on the bearings, or the ends of the 110 rotor.

While I have shown the preferred form of my invention as now known to me, it will be understood that various changes in the construction, combination and arrangement 120 of parts may be made by those skilled in the art, without departing from the spirit of the invention as claimed.

Having thus described my invention, what I claim and desire to secure by Letters Patent is—

1. A rotary pump comprising a main casing formed in two halves, the lower half of which provides a semi-cylindrical inner wall, the upper half being formed with an 130

- inner wall eccentric thereto and uniting with said lower wall to form a complete chamber, grooves having flanges formed along the eccentric upper wall and struck 5 upon an arc concentric with the wall of the lower half, a rotor with engaging flanges mounted within the casing and concentric to the lower wall, a plurality of vanes radially reciprocal within said rotor and 10 adapted to continuously bear against the circular and eccentric walls and cam members against which the inner faces of the vanes rest and by which the vanes are given outward reciprocating movements.
- 15 2. In a rotary pump, an outer casing, a chamber formed therein, a rotor out of the said chamber, a plurality of flanges formed at intervals along said rotor, and grooves formed around the inner wall of said chamber, and within which said flanges rotate to hold the rotor against longitudinal movement.
- 20 3. A rotary pump comprising a casing formed in two parts, the lower half having a concentric inner wall, the upper half having 25 a wall eccentric thereto, the casing here carrying a rotor shaft eccentric to the upper wall, and concentric to the lower wall, a cylindrical rotor mounted upon said shaft, radial slots formed in said rotor, vanes reciprocable in said slots, cams carried upon the casing head and against which the inner faces of the vanes rest while holding the outer faces against the 30 eccentric and concentric portions of the casing wall, a plurality of circular flanges formed along the length of the rotor, and grooves formed in the eccentric portion of the casing walls for the reception of said 35 flanges and whereby end-thrust in the rotor will be obviated.
- 40 4. A rotary pump of the character described including a casing formed in two halves, the lower half of which has a semi-cylindrical inner wall and the upper half 45 being formed with an inner wall eccentric thereto and uniting with said lower wall to form a complete chamber, grooves having flanges and formed with radii eccentric to the upper wall and struck upon an arc concentric with the wall of the lower half, a rotor with engaging flanges turnable within the casing and concentric with the lower wall, cams, the upper peripheries of which are concentric with the inner ends of the 50 grooves, a plurality of vanes radially reciprocal within the rotor and bearing continuously against the circular and eccentric casing walls, and angularly disposed inlet and discharge passages, the outer walls of 55 which are tangent to the inner periphery of the casing.
5. In a rotary pump of the character described, a casing with a smooth cylindrical lower half and a circumferentially 60 channeled upper half eccentric to the lower half, a rotor with engaging flanges journaled axially with the lower half and vanes 65 slidable radially in the rotor and alternately into and out of the channels, an inlet 70 passage to the casing having its outer wall tangent to the casing inner wall and its opposite wall curved from the inlet passage, an outlet passage, the outer wall of which is tangential to the inner wall of the casing 75 and its inner wall meeting the periphery of the rotor at the point where the vanes are withdrawn into it, and an abutment between the two passages.
- In testimony whereof I have hereunto set 80 my hand in the presence of two subscribing witnesses.
